C. R. BUSHNELL

REFRIGERATING APPARATUS

Filed May 15, 1924

UNITED STATES PATENT OFFICE.

CHARLES RICHARD BUSHNELL, OF BEVERLY HILLS, CALIFORNIA.

REFRIGERATING APPARATUS.

Application filed May 15, 1924. Serial No. 713,537.

My invention relates to and has for its purpose the provision of a method of refrigeration, which consists in compressing air, cooling the air through the latent heat of evaporation of a liquid, and then allowing the air to expand in thermal relation to a refrigerant whereby a further cooling of the air is effected and a great reduction in the temperature of the refrigerant.

- 10 It is also a purpose of my invention to provide a refrigerating apparatus by means of which the above method can be carried out, the apparatus having the following advantages: An apparatus requiring a relatively small space and capable of being operated at a relatively low cost; an apparatus in which compressed air is employed as the refrigerating medium and means by which the moisture in the refrigerating medium is eliminated to insure proper operation of the machine; an apparatus in which the air compressed is utilized in its expansion to operate a turbine for creating forced circulation of air over pipes of the abstractor embodied in 25 the apparatus; utilizing the compressed air to agitate and circulate brine or a similar refrigerant through pipes to dissipate heat in a refrigerating chamber; and an apparatus in which the turbine previously mentioned is operatively connected with the compressor to aid the latter in compressing the air, and placing the turbine in circuit communication with the compressor whereby the initial air supplied to the apparatus is reused 30 indefinitely.

I will describe only one method of refrigeration and two refrigerating apparatuses, each embodying my invention, and will then point out the novel features thereof in 40 claims.

In the accompanying drawings—

Figure 1 is a view showing in vertical section one form of refrigerating apparatus embodying my invention;

45 Figure 2 is an enlarged sectional view of one of the pipes of the abstractor shown in Figure 1;

50 Figure 3 is an enlarged fragmentary sectional view of the discharge end of the air conduit and the manner in which it is associated with the intake end of the cooling coil;

Figure 4 is an enlarged fragmentary sec-

tional view of one of the compressor units shown in Figure 1;

55 Figure 5 is a fragmentary sectional view showing a slightly modified form of refrigerating apparatus also embodying my invention.

Referring specifically to the drawings, in which similar reference characters refer to similar parts, my invention in its present embodiment is shown in Figure 1 as comprising a casing C preferably constructed with double walls between which is interposed a 60 heat insulating material 15, and upon this casing is supported the compressor and abstractor embodied in my invention. The compressor comprises, in the present instance, a pair of compressing units designated generally at K and K', and these units are simultaneously operated by a motor M through the medium of a gear 16 fixed to the motor shaft and meshing with a relatively 65 large gear 17 fixed to a shaft 18 provided with a crank 19 engaging the cam member 20 connecting the confronting ends of a pair of piston rods 21. Each compressor unit K or K' comprises a cylinder 22 having a removable head 23 provided with a stuffing box through which moves the corresponding piston rod 21. The end of the rod 21 is provided with a piston head 24 which moves in the cylinder 22 for compressing air when moved in either direction. The cylinder 22 is 70 provided with a porous water jacket 25 to which water is supplied by means of a pipe 26, the porosity of the jacket allowing the slow seepage of water outwardly through the jacket for the purpose of permitting evaporation and to thus utilize the latent heat of evaporation for cooling the cylinder and the compressed air contained therein.

75 The abstractor embodied in my invention comprises pipe units P and P', and each unit consists of two coils of pipe arranged one above the other, and with the coils of the unit P being arranged above the coils of the unit P'. The upper coil 27 of the unit P communicates with the outer end of the cylinder 22 of the unit K through a pipe 28, and a valve 29 allows the passage of compressed air into the pipe from the cylinder but prevents the discharge of air back into the cylinder. It is to be noted that in 80 Figure 1 the valves for the cylinders of the

two units K and K' are indicated diagrammatically by X, but that in Figure 4 the construction of the valves for the cylinder of the unit K' are shown in detail. The other end of the coil 27 is connected to one end of the lower coil 30 of the unit P and this latter coil communicates with the outer end of the cylinder 22 of the unit K'. As shown in Figure 4, a valve 31 allows the 10 exhaust of air from the coil 30 into the cylinder 22, but prevents the retrograde movement of the air back into the pipe. In this manner the coils of the pipe unit P are placed in communication with the cylinders of both compressor units so that the air compressed in the first unit K is conveyed to the second unit K'. As shown in Figure 1, a branch pipe 32 connects the pipe 28 with the cylinder 22 of the unit K' at the inner 15 end of the cylinder 22, and this pipe is provided with a valve 33 (Figure 4) which allows the passage of compressed air from the cylinder into the pipe 28, but prevents discharge of air backward into the cylinder. By this arrangement it will be seen that the air compressed by the piston 24 of the unit K' in moving to the right as when viewed in Figure 1, will find its way to the coil 27 through the pipes 32 and 28.

30 The upper coil 34 of the pipe unit P' communicates at one end with the outer end of the cylinder 22 of the unit K', and as shown in Figure 4 a valve 35 allows the passage of compressed air from the cylinder 35 into the coil, but prevents discharge of air from the coil into the cylinder. The opposite end of the coil 34 is in communication with the lower coil 36 of the unit P' and from this lower coil a pipe 37 extends downwardly through the top wall of the casing C into a tank T containing brine or a similar refrigerant. The lower end of the pipe 37 is provided with a restricted discharge port 38 (Figure 3) which is disposed within the 40 funnel shaped end 39 of a coil pipe 40, the latter being arranged within the casing C and having its opposite end extended into and communicating with the upper portion of the tank T so that the tank is in circuit communication with the coil. The pipe 37 is provided with a branch pipe 41 which is in communication with the housing 42 of a turbine including a plurality of stator and rotor elements 43 which are provided with coacting vanes. The air entering the housing 42 acts on the vanes to effect rotation of a shaft 44 which extends upwardly from the housing through the upper wall of the casing, where it is provided with a fan 45 disposed directly below the pipe units P and P' for creating, when rotated, a circulation of air upwardly over the coils. The air, after acting on the vane elements of the turbine, is discharged from the housing through a 50 pipe 46, such pipe extending upwardly

through the casing and along the top wall thereof for communication with the cylinder 22 of the units K through one way valve 47. In this pipe 46 is arranged an air intake valve 48 which allows air from the atmosphere to be taken into the apparatus until the air within the apparatus reaches a predetermined pressure, when the valve automatically closes. The pipe 46 is provided with a branch pipe 49 in communication 70 with the inner end of the cylinder 22 of the unit K' through a one-way valve 50 (Figure 4), the valves 47 and 50 operating to allow air discharged from the turbine to be returned to the cylinders of the compressor 75 units.

The air discharged through the port 38 and into the coil of pipe 40 functions to effect a forced circulation of the brine in the tank T through the coil so as to be finally 80 discharged back into the tank from the upper end of the coil. The air returned to the tank T is conducted from the tank to the cylinder 22 of the unit K through a pipe 51, a valve 52 preventing the return of 85 air from the cylinder back into the pipe.

The coils of the pipe units P and P', the pipes leading to and from the same, as well as the pipes connecting the tank T and the housing 42 with the compressor units are 90 all provided with water jackets J (Figure 2) which co-operate with the pipes to provide an annular water space communicating with the interior of the cylinder jackets 25 (as shown in Figure 4) so that water supplied to the latter by means of the pipe 26 will be free to circulate around the pipes. The jackets J are formed of porous material to allow the slow seepage of water therethrough with the consequent rapid evaporation of the water so that the latent heat of evaporation can be used in extracting heat from the compressed air traversing the pipes. In connection with the coils of the units P and P' evaporation of the water in the jackets is greatly aided by the current of air generated by the rotating fan 45. For the purpose of subjecting the jackets 25 of the cylinders 22 to currents of air, the absorber and compressor are provided with a cover 53 formed at its ends with openings 54 which allow air to pass into and move horizontally across the water jackets under the action of the fan 45.

To provide an additional cooling action in that portion of the casing C in which the coil 40 is located the casing C is provided with partitions 55 and 56 arranged to substantially enclose the brine tank T. These partitions are formed with openings 55a and 56a, respectively, which allows the circulation of air upwardly past the coil 40 and then downwardly over the surface of the tank T. The tank T may be provided with a pipe 57 which functions as a gage to determine 120

the level of brine within the tank. The housing 42 is likewise provided with a pipe 58 which extends exteriorly of the casing C for the purpose of draining moisture from the housing. A pressure regulating valve 59 is provided in the pipe 37 which is adapted to remain closed until a predetermined pressure of air is built up in the pipes of absorber, when the valve automatically opens and thus allows the compressed air to be supplied to the turbine and tank. The pipe 61 provided with a valve 61^a constitutes an exhaust to atmosphere for the cylinder 22 of the unit K through which air and moisture is discharged from the cylinder and preferably on to the coil 27 thereby providing an additional cooling medium for the air traversing the coil.

In order that the turbine may aid the motor M in actuating the compressor units, I provide a train of gearing 60 which operatively connects the shaft 44 with the shaft of the motor. In this manner the power of the turbine can be utilized to effectively assist the motor in driving the compressor.

The operation of the apparatus is as follows:

Upon operation of the pistons 24 of the units K and K' through energization of the motor M, air is admitted to the pipe 46 through the valve 48 and supplied to the cylinder 22 of the unit K. Under the reciprocating action of the piston 24 the air in the cylinder is compressed and delivered to the unit P and finally to the cylinder 22 of the unit K'. During transit the compressed air, which is naturally heated during operation, is materially reduced in temperature by virtue of the latent heat of evaporation of the water contained in and seeping through the water jacket. This cooled air, after entering the cylinder 22 of the unit K', is ejected therefrom by the piston into the unit P', where it is subjected to the further cooling action of the latent heat of evaporation of the liquid surrounding the coils 34 and 36. The super-cooled air is now delivered to the rotor and stator elements of the turbine for operating the shaft 44 to drive the fan 45 whereby a current of air is caused to traverse the coils of the units P and P' for aiding the evaporation of the water. The compressed and super-cooled air admitted to the housing 42 expands and in so doing effects an extraction of heat from the brine contained in the tank T, thereby greatly reducing the temperature of the brine. The air admitted to the housing 42 constitutes fully a major part of the air traversing the pipe 37, the remainder of the air discharging from the port 38 into the coil 40 and thereby creating a forced circulation of the brine through

the coil for reducing the temperature within the casing C. In traversing the coil the temperature of the compressed air is increased, as will be understood. The air discharged from the housing 42 and the tank T finds its way back to the cylinders 22 of the units K and K' for a second compression, and it is to be noted that by reason of the fact that the pipes 51, 46 and 49 are provided with water jackets that the air traversing the pipes will be further subjected to the heat extraction process by the latent heat of evaporation.

From the foregoing description, taken in connection with the accompanying drawings, it will be manifest that I have provided a method of and apparatus for refrigerating in which compressed air in connection with brine or its equivalent are the sole refrigerating mediums, that the heat is extracted from the compressed air through the latent heat of evaporation of the water in the water jackets and the expansion of the air in the housing 42 of the turbine, and that a further extraction of heat from the brine is effected through its intimate association with the air in traversing the coil 40, and the provision of the water jackets surrounding the air return pipes to the cylinders of the compressor units. Further, it will be manifest that after the air within the apparatus is compressed a predetermined degree the intake valve 48 closes to prevent the further supply of atmospheric air to the apparatus, and that the compressor units, being in circuit communication with the turbine and brine tank, the air originally supplied to the apparatus will be used and reused indefinitely. By using the original quantity of air and removing the moisture therefrom during the passage of the air through the apparatus the air will become thoroughly dried, thus greatly increasing the cooling efficiency of the apparatus. It is to be understood that the valve 48 opens when air pressure in the pipe 46 falls below atmospheric pressure.

Referring now to Figure 5, I have here shown a fragmentary sectional view of a modified form of refrigerating apparatus which is identical to that shown in Figure 1, with the exception that the return pipe 46 is disconnected from the cylinders 22 of the units K and K' for communication with atmosphere, and for the purpose of cooling the surrounding atmosphere. This modified form of my invention is particularly adapted for the cooling of the rooms of buildings, and in this connection the coil 40 may or may not be used, as desired.

Although I have herein shown and described only one method of refrigeration and two forms of refrigerating apparatus, all embodying my invention, it is to be understood that various changes and modifications

may be made herein without departing from the spirit of the invention and the spirit and scope of the appended claims.

Having thus described my invention, I

5 claim:

1. A refrigerating apparatus comprising an air compressor, an abstractor in communication with the compressor and comprising a water jacketed duct, the jacket of 10 which is porous to permit evaporation of the water whereby the air from the compressor is cooled by the latent heat of evaporation of the water, a turbine for creating a forced circulation of air over the abstractor, said 15 turbine receiving the cooled air from the abstractor so as to be operated thereby, a tank confining a refrigerant in surrounding relation to the turbine, means by which the air delivered to the turbine from the ab-

stractor is returned to the compressor, and 20 means for operatively connecting the turbine to the compressor for aiding the latter in compressing the air.

2. A refrigerating apparatus comprising an air compressor, means for extracting heat 25 from the air compressor by the latent heat of evaporation of a liquid, a turbine for creating a forced circulation of air to aid the last means, a brine tank in surrounding relation to the turbine, a coil of pipe in circuit communication with the tank, and a pipe for delivering the cooled compressed air to the turbine for actuating the latter and having one end thereof arranged to discharge air into one end of said coil of pipe 30 so as to create a forced circulation of the brine through the coil of pipe.

CHARLES RICHARD BUSHNELL.
